UNITED STATES PATENT OFFICE.

ANTON WEBER, OF PHILADELPHIA, PENNSYLVANIA, ASSIGNOR TO THE
HEADLY & CARROW MANUFACTURING COMPANY, OF SAME PLACE.

DESIGN FOR SILVERSMITHS' STOCK.

SPECIFICATION forming part of Design No. 21,396, dated March 8, 1892.

Application filed December 26, 1891. Serial No. 416,245. Term of patent 7 years.

To all whom it may concern:

Be it known that I, ANTON WEBER, a citizen of the United States, and a resident of Philadelphia, Pennsylvania, have invented 5 a Design for Silversmiths' Stock, of which the following is a specification.

My design relates to certain ornamentation of silversmiths' stock, and is clearly shown in the accompanying drawings.

10 Figure 1 is a view of the stock in the flat, and Fig. 2 is a view showing it applied to an article.

The term "stock" is used to designate the metal in sheets, from which are formed the 15 different articles known to the trade. The stock here mentioned is particularly adapted as a mounting. The design consists of a stem from which extends a number of branches on

either side, having at intervals scrolls representing leaves and flowers, the spaces between 20 the several branches and scrolls being open to expose the base on which the mounting is set. The sheet may be enlarged by duplicating the design, as shown by dotted lines in Fig. 1.

25 I claim—

The design for silversmiths' stock, as herein shown and described.

In testimony whereof I have signed my name to this specification in the presence of 30 two subscribing witnesses.

ANTON WEBER.
